METHOD OF SETTING TWIST IN THREADS
OR YARNSTheodore H. Story, Merchantville, N. J., assignor
to Radio Corporation of America, a corporation
of Delaware

Application May 30, 1945, Serial No. 596,709

5 Claims. (Cl. 28—72)

1

This invention relates to a method of setting twist in threads or yarns, and more particularly to the method of setting the twist or the balance in yarns or threads of cotton, silk, rayon, nylon, and the like constituted by a plurality of filaments or strands twisted together.

Most yarns or threads are wound in the form of spools in the course of manufacture. During unwinding of twisted yarn, as in weaving fabric therefrom, the difficulty has been experienced that the threads kink or snarl while being unwound and this results in knots or the like which hinder the free use thereof. To overcome this difficulty, it has been proposed to set the balance or the twist by heating the yarn for from 2 to 6 hours, depending upon the particular thread or yarn involved, in humid atmospheres having a relative humidity of 70 per cent or higher. While such processing overcomes the aforementioned difficulty, it is quite time consuming and therefore a definite limitation upon the rate of production of the yarn or thread.

To increase the speed of production of the yarn, it has been proposed to subject the same to treatment in a vacuum. In general, the time required to set the twist is thus cut down to the order of about a half hour after the proper vacuum has been obtained. However, a sizable amount of time is required to create the vacuum, to say nothing of the fact that the high pressure vessels, seals, pumps, and other components of the vacuum systems are quite expensive.

To overcome the foregoing objections, it has been proposed heretofore to place the yarn "packages" or "cakes," as they are known, in wax paper or similar moistureproof bags or envelopes and to subject the packages or cakes to the influence of a high frequency electric field. This field vaporizes the residual moisture in the yarn (which may be of the order of 10 per cent to 14 per cent) and establishes a humid atmosphere within the bag. As the yarn package cools in the presence of the expelled vapor, the twist therein sets more or less. However, this process requires individual handling and wrapping of each of the yarn packages and therefore renders the process expensive, particularly for small packages. Moreover, the wrapping of the individual packages sometimes presents a problem.

The primary object of my present invention is to provide an improved method of setting the twist or balance in yarn, thread or the like of dielectric material which will not be subject to the above mentioned difficulties.

More particularly, it is an object of my present

2

invention to provide an improved method of setting the twist of yarns of dielectric material which will require a much shorter time than is required by prior art methods.

It is also an object of my present invention to provide an improved method of setting the twist of thread, yarn, cord, and the like which can be carried out at relatively low cost and in a highly efficient manner.

10 In accordance with my present invention, I first subject that package of yarn or thread to a substantially uniform high frequency electric field which rapidly heats the dielectric thread substantially uniformly throughout until steam is generated uniformly throughout the entire yarn package. The package is then immediately placed in vessels or chambers having a highly humid atmosphere for sufficient length of time to set the twist. These vessels or chambers may be filled with live steam, for example. The time required to carry out the entire process will vary with the material being treated but will, in all cases, be only about 10 per cent of that required to set the twist by steam alone. Thus, 15 for example, in the case of rayon, the thread can be heated in about a half minute or a minute to 212° F. by reason of the dielectric losses produced in the rayon to thereby vaporize the residual moisture therein, after which the hot package 20 may be placed in a steam room for about 10 minutes. The initial heating (that is, by means of the high frequency electric field) can be carried out in the open or free atmosphere, if desired, so that the packages need not be wrapped or otherwise confined, while the steam heating takes place 25 in a closed or confined vessel. It will be apparent, therefore, that my present invention entirely eliminates the need for wrapping the thread, avoids the use of a vacuum, and yet greatly reduces the time required for the complete process.

40 The novel features that I consider characteristic of my invention are set forth with particularity in the appended claims. The invention itself, however, as well as additional objects and advantages thereof, will best be understood from the following description when read in connection with the accompanying drawing in which

Figure 1 is a partly sectional and partly diagrammatic view of one form of twist setting apparatus for carrying out my present invention,

50 Figure 2 is a top plan view of a portion thereof, and

55 Figure 3 is a view similar to Figure 1 of a somewhat different form of apparatus for carrying out my present invention.

Referring more particularly to the drawing wherein similar reference characters indicate corresponding parts throughout, there is shown a steam chamber 1 which is supplied with steam through an inlet pipe 3 from which the condensed moisture is withdrawn through a pipe 5. The chamber 1 includes a platform or table 7 in alignment with and immediately adjacent to an endless conveyor or belt 9 which passes over an insulated plate 11 and around a pair of pulleys 13, one of which may be power driven. The plate 11 supports an electrode 15 for cooperation with a second electrode 17, both connected through a transformer 19 to a source of high frequency electrical energy 21, such as a vacuum tube oscillation generator. Packages of yarn 23, which may be in the form of spools, bobbins, quills, cones, tubes or the like (formed by winding in a multiplicity of layers a thread or yarn constituted by a plurality of individual filaments or strands which are twisted together) may be placed on the belt 9 which advances them between the electrodes 15 and 17. The uniform, high frequency electric field set up between the electrodes 15 and 17 rapidly heats the packages 23 substantially uniformly throughout the entire length of the thread by reason of the dielectric losses therein and causes the residual moisture in the packages to be vaporized. Beyond the electrodes 15 and 17, the belt 9 advances the packages 23 through an inlet chute 25 into the vessel or chamber 1 which is maintained at a relative humidity of 70 per cent or more. As the packages 23 pass through the chamber 1, they gradually cool and, when they emerge through the exit chute 27, the twist 35 in the threads thereof have become set.

The apparatus shown in Figure 3 is similar to that shown in Figure 1. Here, however, the inlet and exit chutes 25 and 27 are omitted and the steam chamber 1 is provided with inlet and outlet openings 25a and 27a instead. The belt 9a in this modification is arranged to pass through the entire length of the chamber 1 and therefore feeds the packages 23 therethrough in spaced relation to each other, whereas in Figure 1 they 45 are in contact with each other. Also, in the apparatus of Figure 3, the electrodes 15a and 17a are both within the chamber 1, so that the packages 23 are heated by radio frequency energy while they are already exposed to or submerged in the 50 humid atmosphere. As in the case of the system of Figure 1, the packages 23 are heated rapidly by the dielectric losses produced therein when subjected to the high frequency electric field, and, as they cool within the humid atmosphere, the 55 twist in the threads thereof becomes set.

Wherever, in this specification, I have used the terms "yarn," "thread," "cord" and the like, I intend these to be the equivalent of and synonymous with each other, since my present invention 60 is applicable to all, and whether for setting the twist or for effecting the balance thereof. Although I have shown and described two forms of apparatus for carrying out the method of my present invention, it will undoubtedly be apparent to those skilled in the art that many other ways and other forms of apparatus are possible for this purpose. I therefore desire that my invention shall not be limited except insofar as is made necessary by the prior art and by the spirit of 70 the appended claims.

I claim as my invention:

1. The method of setting the twist of thread constituted by a plurality of filaments of dielectric material twisted together which comprises first subjecting said thread, while unconfined, to the influence of a high frequency electric field of sufficient intensity to rapidly heat said thread by reason of the dielectric losses produced therein, and then subjecting the hot thread in a confined region to a humid atmosphere until the twist has been set.

2. The method of setting the twist of moisture containing thread constituted by a plurality of strands of dielectric material twisted together which comprises first subjecting said thread, 15 while unconfined, to the influence of a substantially uniform, high frequency electric field of sufficient intensity to rapidly heat said thread substantially uniformly by reason of the dielectric losses produced therein whereby to substantially uniformly expel moisture from said thread, and then, while said thread is still hot, subjecting it in a confined region to a humid atmosphere until the twist has been set.

3. The method of setting the twist of thread according to claim 2 characterized in that said thread is subjected to said electric field while exposed to the free atmosphere.

4. The method of setting the twist of thread according to claim 2 characterized in that said thread is subjected to said electric field at one location, and characterized further in that the heated thread is substantially instantaneously thereafter transferred to another location to be subjected to said humid atmosphere.

5. Apparatus for setting the twist of thread constituted by a plurality of strands of dielectric material twisted together which comprises means for advancing the thread along a path successively past an unconfined location and a confined location, means for subjecting said thread to the influence of a high frequency electric field at said unconfined location, and means for subjecting said thread to humid atmosphere at said confined location.
